WILLIAM HAGER AND HENRY RIEKERT, OF CINCINNATI, OHIO

AIR-MOISTENING DEVICE FOR COMBUSTION ENGINES

Application filed January 14, 1928. Serial No. 246,834.

This invention relates to a device for moistening air prior to the entry thereof into the cylinders of an internal combustion engine or other device to which it is desired to supply moist air.

An object of the invention is to provide an air moistener which, due to the arrangement and construction of the various parts thereof, will be more efficient than devices of this class heretofore in use.

Another object is to provide a device for the purpose stated which is simple and trouble-proof.

Another object is to provide a device of this kind which will automatically supply ample moisture at all times.

These and other objects are attained by the means described herein and disclosed by the accompanying drawings, in which:—

Fig. 1 is a side elevation, partly in cross section, of the device as used in connection with a carburetor and intake manifold of an internal combustion engine.

The air moistening device of this invention is adapted for use with internal combustion engines. The purpose of the air moistening device is to provide moisture for the air drawn into a carburetor by the suction of the engine. As shown in the drawing, the device may be attached to the inlet port of any carburetor. The device comprises generally an inner bowl 4, an outer bowl 5, a float 6 having associated therewith a needle valve, a quantity of wick material 7 which may be held in position by a screen 8, a fluid supply tank or reservoir 9, and a suitable hood 10, all of which will be set forth in detail presently. The inner bowl 4 is preferably of a cylindrical shape and is provided with a top 11 and a bottom 12. The cylindrical wall 13 is provided with perforations 14 which provide communication with the outer bowl 5. Said bowl 5 is preferably cylindrical in shape, and encircles the inner bowl 4. The wall 15 of the outer bowl is spaced from the cylindrical wall of the inner bowl so as to provide an annular channel 16 into which fluid from the inner bowl may enter.

A connecting member 17 provided with screw threads 18, is secured to the bottom 12 of

the inner bowl. The connecting member is provided with a central bore 19 having communication with a pipe 20 which carries fluid from the supply tank or reservoir 9. By this means the fluid may enter the bowls 4 and 5. If desired a suitable stop cock 21 may be provided for rendering the device inoperative.

Means comprising a float and needle valve are provided for controlling the rate of flow of the liquid into the bowls. Said control means comprises a float 22 having a central longitudinal bore 23 for receiving a reciprocable needle 24, the lower end of which is pointed. Said pointed end of the needle is adapted to enter the bore 19 in the connecting member for impeding the flow of fluid when the float rises to a predetermined level. The connection between the float and the needle comprises an annular grooved collar 25 fixedly secured upon the needle. A plurality of bell crank levers 26 are pivotally secured to the inside surface of the top 11, and are provided with free ends 27 which are received in the grooved collar on the needle. It should be noted that as the float moves upwardly, it will abut the lever 26 at a point 28, thereby turning the lever 26 about its pivotal mounting. The arm of the lever received by the collar 25 will then be moved downwardly for moving the needle point into position for closing the bore 19. A suitable bushing 29 and cap 30 insure alignment and protection to the needle 24 at its end.

A quantity of wick material 7 which may be a sponge or other capillary substance is positioned upon the top 11 of the inner bowl and extends downwardly into the channel 16 provided between the walls of the inner and outer bowl. As shown in the drawing, the fluid 31 rises in the outer bowl to a height determined by the float 6. The portion of wick material extending into the channel is immersed in the liquid, causing saturation of the entire wick by capillary attraction. The screen 8 is positioned over the wick and precludes displacement thereof. Any suitable means such as screws 32 may be provided for securing the screen to the outer bowl wall.

The hood 10 is provided at one end with an enlarged opening 33 into which the wick por-

tion of the device extends. The said opening is of a size sufficient to provide an air channel 34 above and about the wick. If desired suitable baffle plates 35 may be provided upon the inside surface of the hood for deflecting the incoming air toward the wick material, whereby the moistening of said air is effected. At the opposite end of the hood there is provided an opening 36 which communicates with the inlet port 37 of any carburetor 38. The carburetor 38 is connected with the usual intake manifold 39 by means of bolts 40. Any suitable means may be provided for retaining the hood in position upon the carburetor intake port. In the drawing a spring 41 is utilized for the purpose. The spring is so shaped as to contact a lug 42 on the hood, whereby displacement of the hood is precluded.

Any suitable means such as screws 43 may be provided for securing the bowl and sponge elements upon the hood 10. It is evident that as air is drawn into the carburetor through the channel 34 of the hood it will strike the moistened wick material and become saturated before entry thereof into the engine. Great efficiency is obtained because of the construction of this device which presents a comparatively large moistening surface for the incoming air. It is to be understood that various modifications may be made in the structural details of the device without departing from the spirit and scope of the invention.

What is claimed is:

1. In a device of the class described the combination of an inner bowl provided with top, bottom and side walls, an outer bowl communicating with and extending about the inner bowl and forming therewith an annular channel, a bored connection member secured to the bottom wall and adapted for directing through the bore thereof a quantity of fluid from a fluid reservoir, means for controlling the flow of said fluid, comprising a reciprocable needle one end of which may project into the bore of the connection member for closing said bore, a float provided with a longitudinal bore through which the needle may extend, a collar on the needle, levers pivotally mounted on the inner bowl and actuatable by the float for exerting a downward force on the collar and needle for moving the needle toward the bore of the connection member, means for retaining the needle in alignment with the bore of the connection member, a quantity of wick material superimposed upon the top of the inner bowl and extending downwardly into the fluid channel for saturation of the wick, and means for directing air toward the wick prior to the entry of said air into an internal combustion engine.

2. In a device of the class described the combination of an inner bowl provided with top, bottom and side walls, an outer bowl communicating with and extending about

the inner bowl and forming therewith an annular channel, a bored connection member secured to the bottom wall and adapted for directing through the bore thereof a quantity of fluid from a fluid reservoir, means for controlling the flow of said fluid, comprising a reciprocable needle one end of which may project into the bore of the connection member for closing said bore, a float provided with a longitudinal bore through which the needle may extend, a collar on the needle, levers pivotally mounted on the inner bowl and actuatable by the float for exerting a downward force on the collar and needle for moving the needle toward the bore of the connection member, means for retaining the needle in alignment with the bore of the connection member, a quantity of wick material superimposed upon the top of the inner bowl and extending downwardly into the fluid channel for saturation of the wick, a hood having an enlarged open end and a smaller open end, the enlarged open end being adapted to freely receive the wick portion of the device so as to provide an air passage about said wick portion, and the other end of the hood being adapted for connection to a carburetor inlet port, whereby air drawn through the hood into the carburetor port may be moistened by the passage thereof over the moist wick.

3. In a device of the class described the combination of an inner bowl provided with a top, an outer bowl communicating with and extending about the inner bowl and forming therewith an annular channel, means associated with the inner bowl for directing thereinto fluid from a fluid reservoir, a float operated valve for controlling entry of the fluid into the inner bowl, a quantity of wick material supported upon the top of the inner bowl and extending downwardly into the channel whereby the fluid in the channel may saturate the wick, and a hood having communication with a carburetor inlet port and positioned over the wick material for directing air, passing through the hood, against the saturated wick material prior to entry of the air into the carburetor.

4. In a device of the class described the combination of an inner bowl provided with a top, an outer bowl communicating with and extending about the inner bowl and forming therewith an annular channel, means associated with the inner bowl for directing thereinto fluid from a fluid reservoir, a float operated valve for controlling entry of the fluid into the inner bowl, a quantity of wick material supported upon the top of the inner bowl and extending downwardly into the channel whereby the fluid in the channel may saturate the wick, means for holding the wick material in position upon the said top, and a hood having communication with a carburetor inlet port and positioned over the

wick material for directing air, passing through the hood, against the saturated wick material prior to entry of the air into the carburetor.

5. In a device of the class described, the combination of an inner bowl, and an outer bowl having communication therewith, means associated with the inner bowl for directing into the inner bowl fluid from a fluid supply reservoir, a float operated valve within the inner bowl for controlling the quantity of fluid admitted to the bowl, a quantity of wick material extending into and above the outer bowl and adapted for saturation with the fluid, and a hood having communication 10 with a carburetor inlet port and positioned over the wick material for directing air, passing through the hood, against the saturated wick material, whereby to moisten the air before entry thereof into the carburetor.
- 15
20. In testimony whereof, we have hereunto subscribed our names this 12 day of January, 1928.
